UNITED STATES PATENT OFFICE.

RAYMOND M. DE HART, OF AMSTERDAM, NEW YORK, ASSIGNOR TO STEPHEN SANFORD & SONS, INC., OF AMSTERDAM, NEW YORK, A CORPORATION OF NEW YORK.

DESIGN FOR A RUG.

47,323.

Specification for Design.

Patented May 11, 1915.

Application filed March 15, 1915. Serial No. 14,616. Term of patent 3½ years.

To all whom it may concern:

Be it known that I, RAYMOND M. DE HART, a citizen of the United States, residing in the city of Amsterdam, in the county of Montgomery and State of New York, have invented a new, original, and ornamental Design for a Rug of Carpet Sizes, of which the following is a specification, reference being had to the accompanying drawing, forming part thereof.

The drawing illustrates a portion of a rug, showing my new design.

I claim:

The ornamental design for a rug, substantially as shown.

RAYMOND M. DE HART.

Witnesses:

P. S. NEWELL,
W. H. SEALEY.
